UNITED STATES PATENT OFFICE.

ROBERT C. TAFT, OF MOLINE, ILLINOIS.

CAR-UNDERFRAME.

1,311,192.

Specification of Letters Patent. Patented July 29, 1919.

Application filed January 25, 1918. Serial No. 213,679.

To all whom it may concern:

Be it known that I, ROBERT C. TAFT, a citizen of the United States, residing at Moline, in the county of Rock Island and 5 State of Illinois, have invented new and useful Improvements in Car-Underframes, of which the following is a full, clear, and exact description.

My invention relates to improvements in 10 the underframes of cars, and particularly to the construction thereof at the intersections of the body-bolsters and draft members thereof.

One of the most important branches of 15 the mechanical work of a railroad is that of repairing its freight cars. Among other parts it very frequently becomes necessary to replace body-bolsters, and as the latter are of many different designs and constructions 20 varying greatly in width as well as in other respects, it is necessary to maintain the pivotal centers of the car underframes, and not impair the strength and ability of the connections of the bolster to transmit 25 the heavy buffing and pulling strains to which it is subject to the underframe, and to prevent the shearing of the bolts and rivets and the shifting of the bolster and thus putting it out of working order. When 30 the necessity for repairing the car arises it frequently happens that new draft-arms must be used and that these and other materials used for such repairs are not in the possession of the local repair shops where 35 the car became incapacitated and must be sent for and procured from distant sources of supply and thus keep the car idle at a considerable loss to the railroad company.

The object of my invention is to standardize 40 the draft-arms, or draft elements of the underframes of the cars and to use in connection therewith spacing members of various dimensions and construction which will compensate for the differences in the widths 45 of the old and new bolsters; will avoid weaknesses which would develop from such substitution; will avoid the shearing of the bolts and rivets employed in making the connection, and will prevent the shifting of 50 the bolsters. These spacing members or shims are supplied in different sizes to every repair shop on the railroad; and when a car becomes incapacitated anywhere along said road, a new bolster can be immediately substituted, without ordering and waiting for 55 materials, in a comparatively short time.

It is a further object to utilize my improvements in connection with old cars and to utilize the old draft elements thereof wherever possible, and to prevent weakening of 60 the underframe at the intersection of the bolster and draft elements.

The precise constructional details which constitute my invention are hereinafter described with reference to the accompanying 65 drawings, in which—

Figure 1 is a vertical central section of one end portion of the underframe of a railroad car including the intersection of the draft-members and body-bolster showing my improvements applied thereto.

Fig. 2 is a plan view of the said intersecting portion.

Fig. 3 is a vertical central section of a fragment including the intersection of the 75 draft-members and bolsters showing a modified construction of my invention.

Figs. 4 and 5 are similar views showing yet other modifications.

Referring to the construction of the car 80 underframe shown in Figs. 1 and 2 of the drawings, A, A, represent the draft-members or draft-arms or draft-sills; B the flooring, and C', C, the compression member and the tension member, respectively, of a 85 body-bolster. The rear ends of the draft-sills pass between the said compression and tension members, and the upper edges of said draft-sills, where they intersect the transverse vertical plane of said bolster, are 90 built up, as at a, a, and this built up upper edge of each sill is, preferably, ginned into the under surface of the flooring and is provided with a recessed seat d, which latter is 95 of a length slightly greater than the width 95 of the tension member of the bolster, and is of a depth slightly greater than the thickness of the same. Interposed between the edges of seat d and tension member C of the bolster is a shim D which consists of a 100 plate of metal or other suitable material of a length corresponding to the length of seat d into which it is fitted, and of a thickness corresponding to the space between the said tension member and the horizontal edge 105 thereof. The ends e, e, of this shim are thickened and offset upward to provide spacing elements and to fill in between the end edges of said seat and the side edges of 110 the tension member.

The lower edges of the draft-sills are also cut-away to enable them to pass between the

compression and tension members of the bolster and to provide a seat E for a shim F, which latter corresponds in construction and dimensions to shim D, except that its 5 position is the reverse thereof.

Draft-sills A, A, where they cross the bolster, are tied thereto by means of vertical bolts G, G, that pass through the compression and tension members of the bolster 10 and an outwardly projecting flange of the draft-sills substantially as shown in dotted lines in Fig. 1 of the drawings.

If desired, the draft-sills may be provided, beyond where they intersect the bolsters, 15 with suitable rearward extensions H which may be fastened in any manner to wooden or metal center-sills extending from bolster to bolster. The bolster, the draft-sills and the center-sills may be constructed in any 20 desired manner so long as shims D and F are employed in the manner hereinbefore described to supply the discrepancy in the relative proportions of the bolsters and their seats in the draft-sills, and to prevent 25 the consequent loosening of the car structure in the intersection of the bolster and the draft-sills. If it should ever become necessary to replace the old with new bolsters, it is a comparatively easy matter to 30 remove the old shims and substitute shims that would fill the space between the compression and tension members of the bolster and the draft-sills.

In Fig. 3, I show a modified construction 35 of my invention which consists in making seat d of the same length as the width of the compression and tension members 7, 7, of the bolster, and interposing shims 8, 8, between the same and the horizontal edges 40 of said seats that correspond in length to the length of the seat and do not have their ends offset or flanged upward or downward to provide filling members.

In Fig. 4, I show yet another modification 45 of my invention which is designed to be used in conjunction with the underframe of a car in which a cast metal bolster 9 has been substituted. The seat 11 in the lower edges of the draft-sills 10 of this modification 50 are considerably longer than the width of the bolster, and the sides of the edges of said seat are flanged laterally. In this type of underframes the draft-sills pass over the bolster, and the shim 12 used in 55 conjunction therewith is of a length corresponding to the length of said seat and has its rear portion made thicker and stepped downward to form an interposed spacing member 13 that fills in the space between 60 the rear edge of the bolster and the rear edge of the recessed seat. The depth of draft-sills in front of the bolster is greater than at the rear thereof, and at the lower angle of the forward edge of the seat the draft- 65 sills are provided with integral rearwardly

extending lugs 14 whose upper surface is, preferably, in the same horizontal plane as the under surface of the bolster and which is of a length, preferably, corresponding to the distance between the edge of the lower 70 flange of the bolster and the front end of the recessed seat. In order to transmit the shock of the buffing strain from the draft-sills to the bolster, I interpose a stop-block 15 in the space between the bolster and the 75 forward end of the recessed seat. The rear portions of the upper and lower edges of stop-block 15 are rabbeted to form seats for the upper and lower flanges of the bolster, and at the center of height of the rear 80 edge thereof that bears against the vertical web of the bolster, said stop-block is provided with laterally projecting lugs 16 through which horizontal bolts 17 are tapped that secure said block to said bolster. 85

In Fig. 5 I show yet another modification of my invention. This modification is built along the lines of the modification shown in Fig. 4 of the drawings, excepting that the shim 18 has its forward and rear ends 90 thickened and offset downwardly to provide the integral spacing members 19, which, when said shims are properly assembled, are interposed between the forward and rear edges of the tension member of the bolster 95 and the front and rear vertical edges of the recessed seat. This modification does not employ a stop-block between the forward side of the bolster and the forward end of the recessed seat. To compensate 100 for this omission, however, the lower angle of the forward edge of said recessed seat is provided with an integral rearwardly projecting lug 20 that is in the same horizontal plane as the forward flange of the compression member of the bolster against which it bears. This lug 20 and the said forwardly projecting flange of the compression member of the bolster are sandwiched between two tie-plates 21, 22, respectively, by means 105 of a rivet 23 passing through the rear ends of the tie-plates and said flange, and by means of a vertical bolt 24 extending through the draft-sills, the shim, said plates and lug 20. A tie-plate 25 is secured to the underside of spacing-member 19 at the forward end of the shim, and the forwardly projecting flange of the tension member of the bolster is sandwiched between the rear portion of this plate 25 and the shim by means 110 of a vertical bolt 26 that passes through the portion of the draft-sills 10 above the recessed seat, the flanges of said seat, the shim, said forward flange of said tension member and said plate, substantially as shown 115 in said Fig. 5. Rivets 23 and bolts 26 and 27 are adapted to be seated in holes in the draft-sills and bolster that existed before the substitution of the shim, and thus avoid 120 the making of additional holes in these 125 130

members and the consequent weakening thereof. Bolts 27 correspond to bolts 26 and are employed to secure the draft-sills to the upper rear flange or rear portion of 5 the tension member of the bolster, substantially as shown.

The shims constituting the principal feature of my invention may be made of a solid metal plate, of any width or thickness, or 10 they may be made of metal plate recessed or fretted either on their upper or lower surface, or on both upper and lower surfaces. Said shims may have one or both ends offset to provide the spacing elements that are 15 interposed between the front and rear edges of the flanges of the compression and tension members of the bolster and the front end of the seat in the draft-sills, or may be constructed without these elements, and said 20 shims may be seated in recessed seats in the upper and lower edges of draft-sills that pass between the compression and tension members of the bolster, or in the recessed edges of draft-sills that are extended over 25 said bolster, and, finally, said shims may be used either with or without stop-blocks, although it is apparently desirable to employ said block or the equivalent thereof where the draft-sills extend entirely over 30 the bolster. My invention contemplates the use of any of these changes in the construction and uses of the shims.

What I claim as new is:—

1. An underframe for cars comprising a 35 body-bolster, draft-members and shims each consisting of a plate interposed between the horizontal contacting surfaces of said bolster and draft-members.

2. An underframe for cars comprising a 40 body-bolster, draft-members, and shims each consisting of a plate interposed between the horizontal contacting surfaces of said bolster and draft-members and having one end thickened and offset and provided with a 45 shoulder on one horizontal side that engages the adjacent edge of the bolster.

3. An underframe for cars comprising a 50 body-bolster, draft-members, and shims each consisting of a plate interposed between the horizontal contacting surfaces of said bolster and draft-members, both end portions of 55 which are offset toward the same side and provided with shoulders that engage the front and rear edges of said bolster.

4. An underframe for cars comprising a 60 body-bolster, draft-members and shims each consisting of a plate interposed between the horizontal contacting surfaces of said bolster and draft-members and having one of its ends thickened toward one side and provided with a shoulder that engages the adjacent edge of the bolster.

5. An underframe for cars comprising a 65 body-bolster, draft-members each having a recessed seat in an edge thereof the length

of which is not less than the width of the contacting surface of the body-bolster, and shims each consisting of a plate occupying said seat and interposed between the opposing horizontal surfaces of said draft-members and bolster. 70

6. An underframe for cars comprising a body-bolster, draft-members each having a recessed seat in an edge thereof the length of which is greater than the width of the 75 opposing surface of the body-bolster, shims each consisting of a plate occupying said seat and interposed between the opposing horizontal surfaces of said draft-members and bolster, and a spacing member between 80 one side of said bolster and the adjacent end of said seat.

7. An underframe for cars comprising a body-bolster, draft-members each having a recessed seat in an edge thereof the length 85 of which is greater than the width of the opposing surface of the body-bolster, shims each consisting of a plate occupying said seat and interposed between the opposing horizontal surfaces of said draft-members 90 and bolster, and spacing members integral with said shims placed between said bolster and one of the ends of said seat.

8. An underframe for cars comprising a body-bolster, draft-members each having a 95 recessed seat in an edge thereof the length of which is greater than the width of the bolster where it crosses the same, and shims each consisting of a plate occupying said seat and having one end thereof extending 100 beyond the side of the bolster thickened and offset to provide a spacing element between said bolster and the adjacent end of said seat.

9. An underframe for cars comprising a 105 body-bolster, draft-members each having a recessed seat in an edge thereof the length of which is greater than the width of the bolster where it crosses the same, and shims each consisting of a plate occupying said 110 seat and having its ends thickened and offset to provide spacing elements between said bolster and the ends of said seat.

10. An underframe for cars comprising a body-bolster, draft-members having recessed 115 seats in their lower edges where they arch over said bolster which are greater in length than the width of the bolster, and shims each consisting of plates interposed between said bolster and the ends of said seats. 120

11. An underframe for cars comprising a body-bolster having a compression and a tension member, draft-members that pass between the compression and tension members of said bolster and having the upper 125 and lower edges where they pass the same provided with recessed seats, and shims each consisting of plates interposed between the horizontal surfaces of said seats and said compression and tension members. 130

12. An underframe for cars comprising a body-bolster having a compression and a tension member, draft-members that pass between the compression and tension members of said bolster and having the upper and lower edges where they pass the same provided with recessed seats, and shims each consisting of plates interposed between the horizontal surfaces and ends of said seats and the opposing horizontal surfaces and

side edges of said compression and tension members.

In witness whereof I have hereunto set my hand and seal this 14th day of December, 1917.

ROBERT C. TAFT.
